Primary Examiner — Keli L. Hill*(74) Attorney, Agent, or Firm* — KPPB LLP(57) **CLAIM**

The ornamental design for a speaker panel for a playback device, as shown and described.

DESCRIPTION

FIG. 1 is an isometric view of a speaker panel for playback device, showing my new design;

FIG. 2 is a front elevation view thereof;

FIG. 3 is a rear elevation view thereof;

FIG. 4 is an end elevation view thereof;

FIG. 5 is an opposite end elevation view thereof;

FIG. 6 is a top plan view thereof; and,

FIG. 7 is a bottom plan view thereof.

The broken lines shown are included for the purpose of illustrating portions of the speaker panel for playback device that form no part of the claim.
